UNITED STATES PATENT OFFICE

2,361,932

GUN BARREL

Walter M. Fay, Ludlow, Mass.

Application June 13, 1941, Serial No. 397,942

1 Claim. (Cl. 89—14.1)

(Granted under the act of March 3, 1883, as
amended April 30, 1928; 370 O. G. 757)

The invention described herein may be manufactured and used by or for the Government for governmental purposes, without the payment to me of any royalty thereon.

My invention relates to means for cooling a rifle barrel or a machine gun barrel and also to an expedient whereby a rifle or machine gun is lightened in weight without materially affecting the strength of the rifle or machine gun.

An object of my invention is to provide a rifle barrel or a machine gun barrel with a plurality of indentations so that the radiating surface of the barrel is increased.

Another object of my invention is to provide a rifle barrel or machine gun barrel with a plurality of indentations so that a light barrel having a large radiating surface results.

My invention is disclosed in the accompanying drawing and it is to be understood that my invention is not limited to the precise embodiment disclosed but is broad enough to include a range of equivalents as seen from the prior art.

Referring to the accompanying sheet of drawings, Fig. 1 is a side view of a gun barrel broken to show the degree of taper of the barrel and discloses a series of indentations in the barrel of a firearm.

Fig. 2 is a longitudinal sectional view through the center of the barrel.

Fig. 3 is a view taken on the line 3—3 in Fig. 1.

The barrel 10 of a firearm is provided with a series of cup-shaped indentations 12 extending along a line parallel to the axis of the barrel and a series of similarly shaped indentations 13 parallel to the axis of the barrel displaced from the first series of indentations a distance approximately equal to the diameter of the indentations. The two series of indentations are also displaced in a direction extending along the barrel as indicated in Figs. 1 and 3. Adjacent indentations on the barrel bear the same relationship to one

another as the series of indentations 12 bear to the series of indentations 13. It is readily seen from the drawing and description that the indentations are arranged in a "checkerboard" pattern in this preferred embodiment of the invention and it is realized that other indentation patterns might be made of avail in carrying out the broader aspects of my invention.

In this particular embodiment of my invention 10 the barrel of a conventional firearm is provided with a large number of radial holes of sufficient depth, diameter and shape to obtain approximately 100% greater radiating surface and 25% less weight. These holes are located in a geometrical pattern which allows the largest number of holes with the least loss of barrel strength. The bottom of the holes is a sufficient distance from the chamber and bore of the barrel to obtain sufficient strength and maximum heat radiating surface of the barrel.

20 A conventional gun barrel is disclosed in the drawing and the size of the holes in the barrel is drawn in proportion to the inside and outside diameters of the barrel. The actual length 15 of the barrel is approximately 18 times its maximum outside diameter. It is noted that the holes shown in the drawing extend slightly more than one-half the wall thickness of the barrel and yet the strength of the barrel is not seriously 25 impaired.

I claim:

30 An integral gun barrel unit, the envelope of its extreme outer, longitudinal profile being substantially continuous, said barrel unit having numerous radially extending cup-shaped indentations of substantial depth and having inwardly curved bottoms distributed substantially throughout the entire body of the said barrel unit, the 35 indentations terminating within the integral body 40 of the barrel.

WALTER M. FAY.
